THREAD HOLDER FOR WEFT
REPLENISHING LOOMSRichard G. Turner, Worcester, Mass., assignor to
Crompton & Knowles Loom Works, Worcester,
Mass., a corporation of Massachusetts

Application May 17, 1949, Serial No. 93,793

18 Claims. (Cl. 139—257)

1

This invention relates to improvements in thread controls for weft replenishing looms and it is the general object of the invention to provide means by which the thread of the incoming bobbin can be properly placed for shuttle threading on the pick immediately following replenishment and then moved to draw the thread under the fork of the center filling stop motion.

In weft replenishing looms the reserve bobbins are generally stored in a magazine so positioned that bobbin transfer is effected when the lay is at front center. The weft ends of the reserve bobbins extend to some form of thread holder which serves as an anchorage to enable the thread of the transferred bobbin to be at least partly threaded in the eye of the shuttle during the first pick following replenishment. Because of the fact that this thread is not drawn from the selvage as is the case when the shuttle is running on non-replenishing beats of the loom the thread holder must be so placed that the thread can get under the tines of the center filling stop motion fork. It is found however that if a thread holder is in a position favorable for threading of the shuttle it is in a position unfavorable for placing the thread of the freshly transferred bobbin under the filling fork.

It is an important object of the present invention to provide means mounting the thread holder so that it can occupy two different positions one of which is most favorable for shuttle threading and the other of which is most favorable for placement of the thread of the freshly transferred bobbin under the filling fork. Either of these two positions can be the normal position of the holder and mechanism can be provided to move the holder temporarily to the other position, but herein the form of the invention illustrated has the thread holder normally in the position most favorable for placement of the thread under the filling fork and the holder is temporarily moved to a position favorable for shuttle threading.

When the invention is applied to a form of pneumatic thread holder which has gone into general use it is desirable that the length of thread from the bobbins in the magazine through the thread holder receiving mouth to a mass of yarn in a thread collector remain substantially of the same length when the thread holder moves from one of its positions to the other position thereof. This result can be accomplished either by moving the holder and collector together, or the thread holder can be moved independently of the thread collector, in which event it is desirable to provide a form of connection between the thread holder and thread collector which will not materially change the path traversed by the threads from the holder to the collector when the holder moves.

With these and other objects in view which will appear as the description proceeds, the invention resides in the combination and arrangement of parts hereinafter described and set forth.

2

In the accompanying drawings, wherein two forms of the invention are shown,

5 Fig. 1 is a side elevation of part of a weft replenishing loom of well known type with the preferred form of the invention applied thereto, the shuttle box and lay being shown in cross section and the thread holder being shown in a position most favorable for placing the thread of a freshly transferred bobbin under the center filling fork.

10 Fig. 2 is a plan view looking in the direction of arrow 2, Fig. 1, showing the thread holder and thread collector in two different positions.

Fig. 3 is an enlarged front elevation of part of the structure looking in the direction of arrow 3, Fig. 2, the holder for the thread collector being shown in section,

15 Fig. 4 is a detailed vertical section on line 4—4, Fig. 3,

Fig. 5 is a detailed end elevation looking in the 20 direction of arrow 5, Fig. 3, the support arm for the thread collector being shown in section,

Fig. 6 is a view similar to the upper part of Fig. 1 but showing the modified form of the invention wherein the thread holder moves and the thread 25 collector is stationary.

Fig. 7 is a plan view looking in the direction of arrow 1, Fig. 6,

Fig. 8 is a detailed vertical section on line 8—8, Fig. 6,

30 Fig. 9 is a diagrammatic view showing the manner of operation of the modified form of the invention, and

Fig. 10 is a diagrammatic plan showing the 35 relation of the thread holder and filling stop motion in two positions of the lay and holder.

The invention as illustrated is applied to a form of two color weft replenishing loom employing pneumatic thread controls heretofore proposed by me, but the invention is not limited to this type of loom nor is it essential that the 40 previously mentioned thread collector be used in order to attain the advantages of the invention.

Referring more particularly to Figs. 1 and 2, 45 the loom frame 10 supports a magazine M having front and back stacks of reserve bobbins 11 and 12. A transfer arm 13 forming part of a magazine is depressed on weft replenishing beats of the loom by a latch 14 and lay carried bunter 15

50 to place the lowest bobbin in one or the other of the stacks into a shuttle in a shuttle box 16 mounted on a lay 17. The latter is reciprocated by power derived from the top of crank shaft 18 and is ordinarily in front center position when 55 bobbin transfer occurs. As the lay moves rearwardly picking mechanism, designated generally at 19, picks the freshly replenished shuttle out of the box to the opposite side of the loom and the shuttle will complete its travel generally at a

60 time shortly after the lay has passed its bottom center position.

The weft ends W of the bobbins in the magazine extend to a thread holder designated herein

generally at H which in the preferred form of the invention is rigid with a base 20 carrying a hollow thread collector C the upper part of which is connected by means of a flexible hose 21 to an air pump 22 operated by a connector 23 and lever 24 by power derived from the lay. This pump ordinarily creates a partial vacuum in the collector C and thread holder H as the lay moves rearwardly. The weft ends extend through the holder and into the collector and are entangled with a mass of yarn Y in the collector which serves as an anchorage for the re-serve bobbin-weft ends.

The bottom shaft 25 of the loom, completing a rotation every second beat of the loom, has secured thereto a cam 26 which rocks an actuator lever 27 in two pick time during loom operation. This lever has a dog 28 which normally clears a lifting lug 29 on a second normally stationary lever 30, but when weft replenishment is to occur control mechanism 31 directs the dog under the lug 29 to lift the forward or left end of lever 30.

The rear end of lever 30 has an operating pin 35 secured thereto which is normally in raised position but is depressed when lever 30 is rocked preparatory to transfer and will either engage a hook 36 or miss the latter, depending upon the location of a positioning lever 37 controlled by a flexible connector 38 extending to the opposite side of the loom and connected to the shifting shuttle boxes of the loom. When one of the two shuttles of the loom is active the hook 36 will be under pin 35, but when the other shuttle is active the hook will be spaced rearwardly from and out of the path of pin 35.

Secured to the loom frame is a stand 40 on which is rockably mounted a small shaft 41 the outer end of which has secured thereto an arm 42 attached with the upper end of a rod 43 connected to the hook 35. Another arm 44 secured to the shaft 41 is attached by a rod or connector 45 to the magazine M for the purpose of rocking the latter about its pivot 46 when such rocking is necessary. The magazine will ordinarily be at rest and if the shuttle corresponding to one of the stacks of reserve bobbins is active and depleted the magazine remains at rest, the hook 36 under these conditions being out of the path of pin 35, but if the other shuttle is active it will then be necessary to rock the magazine to place the lowest bobbin of the other stack under the transfer arm 13 and under these conditions hook 36 will be depressed by pin 35.

Lever 30 rises on a pick of the loom when a depleted shuttle is approaching the magazine end and the lay is moving forwardly, and raises the latch 14 by a latch lifter 50 connected to the forward end of lever 30. Since the transerrer arm will be in down position when the lay is in front center position on replenishing beats it is necessary to hold the magazine in its abnormal position until after the transerrer arm rises to its normal position, whereupon the magazine can rock back to its normal position. In order to effect this control of the magazine the lever 30 is held with its pin 35 in down position for an interval after the lay has passed front center, after which the lever 27 will rock to permit counter-clockwise movement of lever 30 around its pivot 51 subsequent to completion of a replenishing operation. A spring 52 interposed between lever 30 and a stationary part on the loom frame normally tends to hold lever 30 in the normal idle position shown in Fig. 1 and assists return of

the lever to that position subsequent to replenishment.

Except as noted hereinafter the matter thus far described of itself forms no part of the present invention and may be made as set forth in my prior patents, Nos. 2,128,974 and 2,199,353.

In carrying the preferred form of the invention into effect the base 20 which supports the thread holder and collector is secured to a movable support arm 60 mounted for pivotable movement about a vertical stud 61 carried by a small stand 62 bolted to the loom side 10. A spring 63 interposed between arm 60 and a stand 64 fixed to the loom normally maintains the support arm 60 in the position shown in full lines in Fig. 2 so that the thread collector and holder will be in forward position, such as shown in Fig. 1 and in full lines in Fig. 2. The base 20 is pivoted to the support 60 at 65 for a purpose to be set forth hereinafter.

In order to operate the arm 68 the latter is attached as at 66 to a link 67 extending to an arm 68 freely rotatable on shaft 41. Arm 68 is preferably integral with a second arm 70 the forward end of which is connected to a descending rod 71 connected to a normally closed tension spring 72 the lower end of which is connected by a second rod 73 to the rear arm 74 of lever 30, see Fig. 1.

In order to provide means for limiting the rocking of support arm 60 about its pivot pin 61 front and back stop screws 76 and 77 are mounted in a yoke 78 formed as part of stand 64. By adjusting these screws the location of lever 60 and therefore the thread holder and thread collector can be determined both as to their front and back positions. Thus, by manipulating forward screw 76 it is possible to adjust the front or forward position of the thread holder under action of spring 63 and by varying the rear stop screw 77 the back or rearward position of the thread holder can be determined. This back stop screw will ordinarily be set to limit backward motion of the arm 60 before arm 74 of lever 30 has completed its downward motion, thereby expanding the normally closed tension spring 72.

As set forth herein the normal position of the thread holder and thread collector will be forward, and when a replenishing operation is about to occur rocking of lever 30, acting through rods 71 and 73, will rock levers 68 and 70 in a counter-clockwise direction as viewed in Fig. 1 and exert a pull through link 67 to move the support arm 60 rearwardly, see Fig. 2, thereby moving the collector and holder from their normal forward position I rearwardly to the dotted line position II. Since the forward end of lever 30 will be held in raised position by dog 28 from a time prior to transfer until a point in the loom cycle after completion of the upper movement of transfer arm 13, the thread holder and collector will be held in position II throughout the bobbin transferring and subsequent picking operations. The weft end of the transferred bobbin will therefore be aligned with the shuttle at the time of picking and be in a position favorable for threading of the shuttle. This is shown in Fig. 2, wherein the shuttle S is shown in full lines with the lay on front center and is shown in dotted lines with the lay approximately at top center when picking occurs.

Shortly after picking dog 28 will start to descend and will permit upward movement of link 73 until spring 72 recovers its normal form, after which continued upward motion of the rear end

74 of lever 30 will permit spring 63 to return the carrier arm 60, collector C, and holder H to their forward full line positions shown in Fig. 2. The thread holder will, therefore, return to its forward normal position I at a time occurring not long after the start of the pick, but the precise point at which this return occurs in the loom cycle is not important so long as the thread holder returns to its forward position while the shuttle is still in flight.

By referring to Fig. 10 the reason for this forward motion of the thread holder will be understood. As shown in that figure the shuttle and lay are represented in picking position in full lines and the fork of the filling stop motion is designated as at F. As the lay continues to move rearwardly after picking and the shuttle moves to the opposite side of the loom the lay and shuttle will assume such position as indicated in dotted lines, Fig. 10. The weft thread WT which has been freshly transferred will therefore have that end of it connected to the thread holder moved forwardly from the full line to the dotted line position, Fig. 10, at the same time the lay moves in the opposite or rearward direction. This forward motion enables the weft thread WT to pass under the fork F and the loom can therefore continue to operate. If the thread holder had remained in position II there would be danger that the thread WT would not be able to get under the fork F and the loom would be stopped even though bobbin change and other operations incident to a weft replenishing operation had been perfectly performed.

The previously described pivotal connection 65 comprises a stud 80 extending upwardly through a hub 81 on the base 20 and having a head 82 on the base 20 extending over the hub. A nut 83 fastens the stud to the support 60 as shown for instance in Fig. 3.

The base 20 has an arm 85 extending to the right therefrom as viewed in Fig. 2 and connected to a rod 86 pivoted as at 87 to the bracket 64. The purpose of the link 86 is to cause the thread collector C and the holder H to move in such manner as to require little or no change in the length of the weft threads from the bobbins in the magazine through the holder to the mass of yarn in the collector when the holder moves from position I to position II. This will be apparent from the dotted line position in Fig. 2 where it will be noted that the holder is in about the same position lengthwise of the lay when in positions I and II.

In the modified form of the invention the thread collector is kept stationary and the thread holder only is moved. As shown more particularly in Fig. 7, the bracket 40 has a bearing member 90 secured thereto as at 91 provided with a rock shaft 92 to which is secured an arm 93 connected to the aforesaid rod 71. A second arm 94 secured to the other end of the rock shaft 92 has a pin and slot connection 95 with a sliding carrier 96 on which the holder H1 is mounted. The carrier 96, see Fig. 8, is held in position by a guide cap 97 secured as at 98 to the base 20. A flexible hollow thread conductor 99 connects holder H1 to the collector C. The weft ends from the reserve bobbins pass through the holder, flexible connector 99, and into the collector to be entangled with the mass of yarn Y therein.

Under normal conditions the thread holder will be in the full line position III shown in Fig. 9, but when a weft replenishing operation occurs downward motion of rod 71 will rock shaft

92 to cause arm 94 to swing to the right, or to the dotted line position, thereby moving the holder to position IV. As the holder moves from one of these positions to the other the flexible yarn conductor 99 will bend on itself to some such shape as indicated in Fig. 9.

The holder of the modified form of the invention moves in substantially the same time as do the holder and collector in the preferred form, i. e., the holder will be in the dotted line position IV, Fig. 9, during a transferring operation and will remain in that position until the shuttle is picked, after which the holder will return to the full line position III for the purpose of assisting the thread of the freshly transferred bobbin to move under the filling fork F, Fig. 10. The guide cap 97 requires the carrier 96 to move in a direction which is substantially perpendicular to the weft ends extending from the reserve bobbins, hence there will be no material change in the length of thread from the magazine to the thread collector.

From the foregoing it will be seen that the invention sets forth mechanism by which the thread holder can occupy two positions in one of which it is most favorably located for threading of the shuttle immediately after weft replenishing and in the other of which it assists the thread of the freshly transferred bobbin to move under the filling fork F. In both the preferred and modified forms of the invention the thread holder is so controlled in its movements as to preserve without substantial change the length of the paths traversed by the weft ends of the reserve bobbins from the magazine to the thread collector. In the preferred form of the invention the collector and the holder move bodily, while in the modified form the collector is maintained stationary and the thread holder only moves. The spring 72 between rods 71 and 73 is extended during the latter part of the downward motion of arm 74 of lever 30 so that the holder can be maintained in its rearward position sufficiently long to assist in threading the shuttle. The holder is preferably so controlled that it returns to its forward position during the flight of the shuttle and the thread holder contribute to moving the thread of the freshly transferred shuttle under the fork F, as shown in dotted lines at WT, Fig. 10.

Having thus described the invention it will be seen that changes and modifications of the foregoing specific disclosure may be made without departing from the spirit and scope of the invention.

What is claimed as new is:

1. In a weft replenishing loom having a reserve bobbin magazine from which weft ends extend and having a backwardly and forwardly reciprocating lay provided with a center filling fork, a thread holder for said weft ends, means mounting the thread holder for movement backwardly and forwardly in the loom, and means cooperating with the mounting means effecting backward motion of the thread holder to a position to facilitate threading of a shuttle during the first pick thereof subsequent to replenishment thereof with a bobbin from the magazine and thereafter effecting forward motion of the thread holder to a position to facilitate movement of the thread of the shuttle under said filling fork.
2. In a weft replenishing loom having a lay provided with a center filling fork which moves to

detecting position to detect presence of weft in the warp shed during forward movement of the lay, the loom having a reserve bobbin magazine from which weft ends extend to a thread holder, means mounting the thread holder for location in one position favorable for shuttle threading and location in another position favorable for movement under the filling fork of a weft end extending from the holder to a freshly replenished shuttle subsequent to picking of the shuttle, and means effective incident to a replenishing operation of the loom cooperating with said mounting means to effect location of the thread holder in said one position prior to picking of the shuttle and effect location of said thread holder in said other position thereof prior to movement of the filling fork to the detecting position thereof during the next forward movement of the lay.

3. In a weft replenishing loom provided with weft replenishing mechanism including a reserve bobbin magazine from which weft ends extend, the loom having a backwardly and forwardly reciprocating lay provided with a center filling fork, a thread holder for the weft ends mounted for movement to either a rearward or a forward position, a shuttle replenished by a bobbin from the magazine by the replenishing mechanism when the lay is on front center being picked during a rearward movement of the lay following replenishment of the shuttle, and means controlled by the replenishing mechanism effecting location of the thread holder in said rearward position thereof during the rearward motion of the lay when the replenished shuttle is picked to facilitate threading of the shuttle and thereafter effect location of the thread holder in said forward position thereof to facilitate movement of the thread of the shuttle under said filling fork.

4. In a weft replenishing loom having a backwardly and forwardly reciprocating lay provided with a center filling fork which periodically moves to detecting position to detect presence of weft in the warp shed, the loom having a reserve bobbin magazine from which weft ends extend, a thread holder for the weft ends movably mounted for location in either a rearward or a forward position, a shuttle replenished by a bobbin from the magazine when the lay is on front center being picked during rearward movement of the lay immediately following replenishment, and control means for the thread holder causing the latter to be in said rearward position thereof during rearward motion of the lay immediately following a weft replenishing operation to facilitate threading of the shuttle and thereafter causing the thread holder to be in said forward position thereof to facilitate movement of the thread of the shuttle under the filling fork prior to movement of the latter to the detecting position thereof following weft replenishment of the shuttle.

5. In a weft replenishing loom having a freshly replenished shuttle from which a weft end extends to a thread holder and wherein the shuttle is picked during a rearward motion of a substantially horizontally reciprocating lay provided with a filling fork which moves to detecting position to detect the presence of weft in the warp shed during forward movement of the lay, means mounting the thread holder for motion relatively to the loom to either a forward or a rearward position, and means cooperating with said mounting means causing the thread holder to be in the rearward position thereof during the rearward motion of the lay when the shuttle is picked and

subsequently causing the thread holder to be in the forward position thereof prior to movement of the filling fork to the detecting position thereof on the forward movement of the lay next following picking of the replenished shuttle.

6. In a weft replenishing loom having a reserve bobbin magazine from which weft ends extend and having a backwardly and forwardly reciprocating lay provided with a center filling fork, a thread holder for said weft ends, a thread collector containing a mass of yarn, the weft ends extending from the magazine through the thread holder into the collector to said mass of yarn, a mounting for said thread holder and thread collector movable to locate the thread holder in backward or forward position in the loom and so constructed that the length of the weft ends from the reserve bobbins to said mass of yarn remains substantially the same whether the thread holder is in the backward or forward position thereof, and means cooperating with said mounting moving the thread holder to the backward position thereof favorable for threading a shuttle replenished by a bobbin from the magazine and thereafter moving the thread holder to the forward position thereof favorable for movement of the thread extending from the thread holder to the shuttle under said filling fork.

7. In a weft replenishing loom having a backwardly and forwardly reciprocating lay provided with a center filling fork, the loom having a reserve bobbin magazine from which weft ends extend, a stationary thread collector having a mass of yarn therein, a thread holder intermediate the thread collector and magazine, means mounting the thread holder for movement to rearward and forward positions in the loom, a hollow flexible connector means between the thread holder and the collector, the weft ends extending from the magazine through the thread holder and connector means to said mass of yarn in the collector, said mounting means being so constructed that the path traversed by the weft ends from the magazine through the thread holder and flexible connector to said mass of yarn in the collector remaining substantially the same whether the thread holder be in the forward or rearward position thereof, and means cooperating with the mounting means causing the thread holder to be in said rear position favorable for threading a shuttle replenished by a bobbin from the magazine and thereafter causing the thread holder to be in said forward position favorable for movement of the weft end extending from the holder to the shuttle under said filling fork.

8. In a weft replenishing loom having a backwardly and forwardly reciprocating lay provided with a center filling fork, the loom having a reserve bobbin magazine from which weft ends extend, a pneumatic thread holder into which the weft ends extend pneumatically tensioning the weft ends, means mounting the thread holder for movement to rearward and forward positions, and means cooperating with the mounting means causing the thread holder to be in rearward position to facilitate threading of a shuttle replenished by a bobbin from the magazine and thereafter causing said thread holder to be in forward position, the thread holder due to the forward position thereof and said pneumatic tensioning tending to draw the thread extending from the thread holder to the shuttle under the filling fork.

9. In a weft replenishing loom having a backwardly and forwardly reciprocating lay provided

9

with a center filling fork, the loom having a reserve bobbin magazine from which weft ends extend, a thread holder for the weft ends, means normally supporting the thread holder in forward position but capable of movement to locate the thread holder in a rearward position, and means cooperating with said mounting means causing the thread holder to be in said rearward position to facilitate threading of a freshly replenished shuttle and thereafter effecting return of the thread holder to the normal position thereof to facilitate movement of the thread extending from the thread holder to the shuttle under the filling fork.

10. In a weft replenishing loom having a backwardly and forwardly reciprocating lay provided with a center filling fork, the loom having a reserve bobbin magazine from which weft ends extend, a thread holder for said weft ends, means mounting said thread holder for location in either a forward or a rearward position in the loom, means normally holding the mounting means in position to locate the thread holder in the forward position thereof, a normally stationary lever having an operative movement incident to a weft replenishing operation of the loom, and connections between said lever and said mounting means effective due to movement of the lever incident to a weft replenishing operation of the loom to effect movement of the thread holder to the rearward position thereof to facilitate threading of a freshly replenished shuttle when the latter is picked and thereafter cooperating with said second named means to effect return of the thread holder to the normal forward position thereof to facilitate movement of the thread extending from the thread holder to the shuttle under said filling fork.

11. In a weft replenishing loom having a reserve bobbin magazine from which weft ends extend and having a backwardly and forwardly reciprocating lay provided with a center filling fork, a thread holder for said weft ends, means mounting the thread holder for movement backwardly and forwardly in the loom, and means cooperating with the mounting means effecting backward motion of the thread holder to a position to facilitate threading of a shuttle freshly replenished by a bobbin from the magazine when said shuttle is picked and thereafter effecting forward motion of the thread holder to a position to facilitate movement of the thread extending from the thread holder to the shuttle under the filling fork while the shuttle is in flight.

12. In thread control means for a weft replenishing loom having a backwardly and forwardly reciprocating lay provided with a filling stop motion and wherein a thread extends to a shuttle on the lay subsequent to a weft replenishing operation and the shuttle is picked during backward motion of the lay, means engaging the thread movable to determine the position of the thread with respect to the lay, and control mechanism for the means causing the latter to position the thread in a relatively rearward position favorable for threading of the shuttle at the time of picking and subsequent to picking causing the means to position the thread in a relatively forward position favorable to cooperation of the thread with the filling stop motion.

13. The method of controlling the thread of the incoming bobbin in a weft replenishing loom operating with a center filling fork and having a lay which swings between front and back center positions, the method consisting in the following

10

steps: holding an end of the thread at a point above but intermediate the front and back center positions of the lay, picking the shuttle when the lay is at approximately said point to effect threading of the shuttle, moving the held end of the thread forwardly, and thereafter lowering the filling fork to detect presence of weft in the warp shed after the shuttle has passed the fork.

14. The method of controlling the thread of the incoming bobbin in a weft replenishing loom operating with a center filling fork and having a lay which swings between front and back center positions, the method consisting in the following steps: holding an end of the thread above the lay at approximately the point between the back and front center positions of the lay which the latter occupies when the shuttle is picked, picking the shuttle to effect threading of the shuttle, moving the held end of the thread forwardly, and thereafter dropping the filling fork to detect the presence of weft in the warp shed.

15. The method of controlling the thread of the incoming bobbin in a weft replenishing loom operating with a center filling fork and having a lay which swings between front and back center positions, the method consisting in the following steps: holding an end of the thread at a point corresponding to the position the lay occupies when the shuttle is picked, picking the shuttle to effect threading thereof, thereafter moving said held end of the thread frontwardly, and thereafter dropping the filling fork to detect presence of weft in the warp shed while the shuttle is still in flight.

16. The method of controlling the thread of the incoming bobbin in a weft replenishing loom operating with a center filling fork and having a lay which swings between front and back center positions, the method consisting in the following steps: holding an end of the thread above the lay at a point which the latter occupies when the shuttle is picked, picking the shuttle to effect threading thereof, moving said held end of the thread in a direction to move the thread toward the filling fork while the shuttle is in flight, and thereafter drop the filling fork to detect the presence of weft in the warp shed after the shuttle has passed the filling fork.

17. In a pneumatic thread holder and collector unit for a weft replenishing loom, a stand adapted for attachment to the loom frame, a support arm pivoted to the stand, a pneumatic thread holder, a pneumatic thread collector pneumatically connected to the holder, a base supporting the holder and collector, a pivotal connection between the base and the support arm, and a link having one end thereof pivoted to the base at one side of said pivotal connection and having the other end thereof adapted for pivotal movement about a point fixed with respect to the stand.

18. The method of controlling the thread of a bobbin freshly inserted into a shuttle in a weft replenishing loom operating with a filling fork on a lay, the method consisting in the following steps: locating the thread favorably for threading of the shuttle when the latter is picked, picking the shuttle, effecting movement of the thread forwardly to a position favorable for cooperation with the filling fork, and thereafter causing the fork to detect the presence of the thread in the warp shed after the shuttle has passed the fork.
